US00D695307S

(12) **United States Design Patent**
Wu(10) **Patent No.:** **US D695,307 S**
(45) **Date of Patent:** **** Dec. 10, 2013**

- (54) **DISPLAY SCREEN WITH AN ICON**
- (75) Inventor: **Nancy Sandra Wu**, Vancouver (CA)
- (73) Assignee: **Webtech Wireless Inc.**, Burnaby (CA)
- (**) Term: **14 Years**
- (21) Appl. No.: **29/407,447**
- (22) Filed: **Nov. 29, 2011**
- (51) **LOC (9) Cl.** **14-04**
- (52) **U.S. Cl.**
USPC **D14/491**
- (58) **Field of Classification Search**
USPC D14/485-495; 715/700-867
